UNITED STATES PATENT OFFICE.

BERNARD H. SKELLY, OF BRIDGEPORT, CONNECTICUT.

TOY TRAFFIC SIGNAL.

Application filed November 4, 1925. Serial No. 66,781.

This invention has reference to toy semaphore signals, but more particularly comprises the representation of the figure of a traffic officer mounted on a base and manually controlled means for operating the signal.

The object is to provide an exceedingly cheap and amusing toy, not at all likely to get out of order and readily operated.

10 In the accompanying drawing Figure 1 is a front elevation illustrating the invention.

Figure 2 a rear view.

15 Figure 3 a view similar to Figure 1 but illustrating the semaphore after operation, and

Figure 4 is a rear perspective of the construction shown at Figure 3.

Similar numerals of reference denote like 20 parts in the several figures of the drawing.

1 represents the figure of a traffic officer mounted on a base 2 and having one arm 3 pivoted at its upper end to the shoulder of the figure at the rear thereof.

25 4 is a vertical standard or rod journaled at the lower end in the base 2 and carrying at the top the conventional "Stop" and "Go" signals, and from a stationary arm 5 of the figure extends a member that terminates in a vertically disposed socket 6 through which the rod extends freely, the function of this 30 socket being, of course, to support the rod. This socket being painted white fairly represents the gloved hand of the figure embracing the rod, thus carrying out the semblance of a traffic officer.

35 7 is an operating lever pivoted to a clip 8 that is secured to the back of the figure the arm being confined between the clip and 40 the figure itself so as to prevent undue wobbling.

The rear of the pivoted arm 3 near its upper extremity beyond the pivotal point has a lip 9, and one extremity of the lever 45 7 normally extends immediately beneath this lip, while the other extremity of said lever normally extends outwardly beyond the figure and is curved as shown and is within the field of a crank member 10 that 50 extends from the rod 4.

The parts being in the position as shown at Figure 1, the operation of the semaphore is effected by swinging the crank 10 rearwardly so that it will strike the projecting end of the lever 7, swing it on its pivotal point and thereby cause the other end of

the lever to operate against the lip 9 and effect the elevation of the pivoted arm so that the parts will be in the position shown at Figure 3.

In order to keep the pivoted arm steady in its movements, the adjacent extremity of the lever has a slot 11 formed therein through which projects the pin 12 that serves as the pivot for the arm 3, this construction being preferred although it is not absolutely necessary.

When the crank is swung forwardly the pivoted arm and its operating lever will return by gravity to their normal position.

What is claimed is:

1. A toy traffic signal, comprising the figure of a traffic officer mounted on a base, an arm pivoted to the shoulder of said figure and having a lip outside the pivotal point, a lever pivoted to the back of said figure and having one end extending beyond the side of said figure while the other end is immediately below said lip, and a vertical rod journaled to revolve in said base and having a crank extending therefrom and carrying at the top a conventional "Stop" and "Go" signal, whereby, when said crank is swung rearwardly it will operate the signal to "Stop" position and will strike the extension of said lever and effect the raising of said arm.

2. A toy traffic signal, comprising the figure of a traffic officer mounted on a base and having one arm pivoted to the shoulder of said figure while the other arm has a forwardly projecting part that is formed into a vertically disposed socket, an upright rod journaled to revolve in said base and extending through said socket and carrying at its upper end the conventional "Stop" and "Go" signals and having a crank portion, a lever pivoted to the back of said figure and having one end extending within the field of said crank while the other end is operatively related to said pivoted arm, whereby,

when said crank is swung rearwardly it will expose the "Stop" signal and will strike the extending portion of said lever and thereby cause the other end of the latter to swing upwardly and raise the pivoted arm, while the forward swing of said crank will permit said lever and arm to assume their normal positions by gravity and will revolve said rod to expose the "Go" signal.

3. A toy traffic signal, comprising the figure of a traffic officer mounted on a base, an

arm pivoted to a shoulder of said figure, a vertical rotary rod rising from said base and having a crank extension and carrying at the top legendary signals, and a lever 5 pivoted to said figure with one end adjacent said arm and the other end within the field of operation of said crank whereby

the swing of the latter will effect the operation of the signals and the elevation and dropping of said arm.

10 In testimony whereof I affix my signature hereto.

BERNARD H. SKELLY.
